BOTTLE

Massimo Vignelli, New York, N.Y., assignor to The Gillette Company, Boston, Mass., a corporation of Delaware

Filed Feb. 8, 1968, Ser. No. 10,501

Term of patent 14 years

Int. Cl. D9—01

U.S. Cl. D9—169

Fig. 2

Fig. 3

FIG. 1 is an elevational view of a bottle, showing my new design;

FIG. 2 is a top plan view; and

FIG. 3 is a sectional view taken on the line 3—3 of FIG. 2.

The lines on the bottle indicate shallow irregular grooved deformations.

I claim:

The ornamental design for a bottle, substantially as shown and described.
